CLAIM

The ornamental design for a stand for toy beads, as shown and described.

DESCRIPTION

FIG. 1 is a perspective view of portions of the front, top, and right side of a stand for toy beads showing my new design; FIG. 2 is a perspective view of portions of the rear, bottom, and right side thereof;

FIG. 3 is a front view thereof;

FIG. 4 is a rear view thereof;

FIG. 5 is a top plan view thereof;

FIG. 6 is a bottom view thereof;

FIG. 7 is a right side view thereof;

FIG. 8 is a left side view thereof; and,

FIG. 9 is a perspective view of the stand for toy beads of FIG. 1 attaching others stands drawn in broken lines.

The broken lines shown are included for the purpose of illustrating portions of the article which form no part of the claimed design.
